F. HOFMANN

APPARATUS FOR LEVELING SOLES OF SHOES

Filed March 14, 1924

FIG. 1.

FIG. 2.

INVENTOR.
Friedrich Hofmann

BY
Gen. C. Heinrich
ATTORNEY.

Patented Dec. 29, 1925.

1,567,645

UNITED STATES PATENT OFFICE.

FRIEDRICH HOFMANN, OF SCHMOELLN, GERMANY.

APPARATUS FOR LEVELING SOLES OF SHOES.

Application filed March 14, 1924. Serial No. 699,206.

To all whom it may concern:

Be it known that I, FRIEDRICH HOFMANN, a citizen of the Republic of Germany, residing at Schmoelln, Saxony-Altenburg, 5 Republic of Germany, have invented certain new and useful Improvements in an Apparatus for Leveling Soles of Shoes (for which I have filed application in Germany on March 12, 1923), of which the following is a specification.

This invention relates to an apparatus for leveling the soles of shoes or the like, and it is the principal object of the invention to provide an apparatus of this type allowing 15 a simultaneous tensioning of the leveling roller against the work-piece and a proper adjustment of the latter.

Another object of the invention is the provision of an apparatus of this character with 20 means for locking the parts in their adjusted positions.

A further object of the invention is the provision of a padded, adjustable abutment for the shoes.

25 These and other objects and advantages of my invention will become more fully known as the description thereof proceeds and will then be specifically pointed out in the appended claims.

30 In the accompanying drawing, forming a material part of this disclosure:

Figure 1 is a side elevation of an apparatus for leveling soles of shoes, constructed according to the present invention.

35 Figure 2 is a front view thereof.

A frame or table *a* of any well known suitable construction, for instance as shown in the drawing, has attached thereto a bracket *a'* having an upper inclined bar 40 adapted to pass through the lower end of an arm *b* which carries at its upper end a support *b'* presenting an abutment for the shoe and on which a piece of felt *c* or the like is mounted against which the shoe *d* is 45 adapted to be pressed.

At the lower part of the table *a* a foot operated lever *e* is pivotally mounted intermediate its ends in a bracket *e''* attached to the table. To the rear end of the foot lever 50 *e* a rod *f* is movably secured, and a spring *g* is wound about this rod, the lower end of which spring engages a collar *g'* on said rod, while the upper end of the spring engages the lower end of a sleeve *h* in which 55 the upper end of the rod *f* is movably guided. The sleeve *h* is connected with a leveling

roller *i* by means of an arm *k*, one end of which is pivotally secured to the sleeve *h*, while the opposite end thereof carries the roller *i* which is equipped with handles *l* 60 allowing an operation or execution of a reciprocatory movement of the roller *i* by hand.

Intermediate its ends the arm *k* has attached thereto at both of its sides arms *m*, pivotally secured at their upper ends to said 65 arm, and with their lower ends pivotally attached to the sides of the table legs. The movement of the arms *m* is limited according to the size of the shoe on the last by means of a set screw *a''* or the like, carrying 70 the customary locking nuts for locking the set screw in its adjusted positions.

A draw bar or bolt *p* is threaded with one of its ends into a sleeve *p'* to which is pivotally secured the lower end of an arm *o'* 75 which carries the shaft *o* of the last *n* for the shoe *d* at its upper end, while its lower end is pivotally secured, as at *r* to arm *o'*. The opposite end of bolt *p* is attached to the hooked end of an element or member *p''*, 80 pivotally secured to a bracket *m'* on foot lever *e*.

A stop rod *e'* has a lower shoulder which is adapted to be engaged by the foot lever *e* when the latter is depressed in order to 85 lock the same.

In operation, the foot lever *e* is depressed and locked by its engagement with the shoulder of the stop rod *e'* whereby the arm *k* and leveling roller *i* will be held under the 90 tension of the spring *g* against the shoe or work-piece *d*, while the last *n* carrying the shoe is firmly held against the felt piece *c* on support *b'*. It will be clear that in this manner the working tool is pressed against 95 the work-piece, and the latter is held in its proper position by one operation, while the movements of arms *m* are adapted to be adjusted in certain limits according to the size of the shoe by means of screw *a''*. 100

It will be clear that changes may be made in the general construction and in the arrangement and construction of the minor details of the device within the scope defined by the appended claims without departing 105 from the spirit of the invention.

Having thus described my invention, what I claim as new, and desire to secure by Letters Patent is:

1. In an apparatus for leveling the soles 110 of shoes having a hand-operated leveling roller, a foot lever for yieldingly pressing

said leveling roller against the sole, a last, a two-armed lever supporting said last, a toe abutment for the shoe held on said last, and a means for simultaneously pressing 5 said last and the shoe thereon against said toe abutment, and said leveling roller against the sole upon the operation of said foot lever.

2. In an apparatus for leveling soles of 10 shoes having a hand operated leveling roller, a foot lever for yieldingly pressing said leveling roller against the sole to be leveled,

an articulated last support, a cushioned toe abutment for the shoe on the last on said last support, and a connection between said last support and said foot lever for allowing a simultaneous pressing of said leveling roller against the sole of the shoe and of the shoe on the last against the toe abutment upon the operation of said foot lever. 15 20

In testimony whereof I affix my signature.

FRIEDRICH HOFMANN.
